UNITED STATES PATENT OFFICE.

WILLIAM DIETER, OF BROOKLYN, NEW YORK.

MEANS FOR SPINNING GYROSCOPES AND LAUNCHING TORPEDOES.

1,402,745.

Specification of Letters Patent. Patented Jan. 10, 1922.

Application filed January 15, 1920. Serial No. 351,523.

To all whom it may concern:

Be it known that I, WILLIAM DIETER, a citizen of the United States of America, residing in the borough of Brooklyn, county 5 of Kings, city and State of New York, have invented certain new and useful Improvements in Means for Spinning Gyroscopes and Launching Torpedoes, of which the following is a specification.

- 10 This invention relates to means for launching torpedoes, such as the Bliss-Leavitt torpedo, wherein the gyroscope is spun up by means of compressed air. Ordinarily such spinning up is performed during the act of 15 launching, that is, while the torpedo is moving out through the launching tube; the action of the trip dog or hook which opens the starting valve in the torpedo admits compressed air to the spinning up turbine of the 20 gyroscope, which spins up the gyroscope, and after imparting to it a prescribed number of turns sufficient to bring it up to full speed, automatically shuts off the air and unlocks the gyroscope. This unlocking occurs before the torpedo has left the tube, or, 25 in any event, before it has lost the direction imparted to it by the launching tube; so that this direction is impressed upon the gyroscope at the instant when it is unlocked. 30 According to the present invention, instead of spinning up the gyroscope while the torpedo is being launched, this spinning up is accomplished, or at least started, before the launching operation begins. The compressed 35 air for spinning up the gyroscope, instead of being taken from the torpedo flask, is taken from a distinct source of compressed air exterior to the torpedo and pertaining to, or adjacent to, the launching tube. In the 40 act of launching, the first operation is to turn air from such independent reservoir into the torpedo, where it operates the spinning-up turbine. The operation by which the compressed air (or other gas under pressure) is admitted to the launching tube to 45 expel the torpedo, occurs after the initiating of such spinning-up operation, and may follow it after a longer or shorter interval of time, as determined by the operator. In 50 carrying out this invention I provide a separable compressed air connection between the special reservoir of compressed air and the torpedo; this connection comprises preferably, a slip or telescopic joint between the 55 breech portion of the launching tube and some part of the torpedo near its stern

through which connection the compressed air passes until the instant of beginning launching, when the connection readily separates. Preferably the same controlling means determines both the admission of air for spinning up the gyroscope, and the subsequent admission of air for launching the torpedo. 60

The invention is applicable to both above-water and submersed launching tubes. 65

In the accompanying drawings,—

Figure 1 is a sectional elevation showing a part of the launching tube with the aft portion of the torpedo within it ready for launching; 70

Fig. 2 shows on a larger scale the controlling means in elevation, and the special compressed air tank in vertical section;

Fig. 3 shows in longitudinal section the telescopic slip joint; 75

Fig. 4 shows the same in cross-section on line 4—4 in Fig. 3.

Referring first to Fig. 1, A is the torpedo. B the launching tube, C the usual tank pertaining to the launching tube for supplying compressed air for launching, D the usual launching valve controlling the flow of air from C to B, E the valve-operating rod, F the valve-operating lever with its locking sector G, and H the usual trip lever for holding this sector normally locked and unlocking it when launching is to occur. All of these parts are of the usual construction, except in the respects hereinafter stated. As usual, the lever F has a downwardly-projecting arm 'F' connected through a rod I to the usual torpedo lock which prevents the accidental forward movement of the torpedo while in the launching tube, such lock being ultimately withdrawn by the operation of the lever F to open the valve D. The opening of the valve D permits compressed air to pass from the tank C through a passage in the casting J which connects the tank with the launching tube, this passage leading from the tank to the valve and thence from the valve to the breech portion of the launching tube. 95

According to the present invention it is preferable to provide a special compressed air tank K for containing the air to be used for spinning the gyroscope. In practice a pressure of about 2,800 lbs. per square inch is found suitable. For practical purposes, it is preferable to have the tank K separate from any other reservoir of compressed air. 105 At the outlet from the tank K is a valve 110

L which controls the outflow of compressed air through pipe M to a part N located in the breech portion of the launching tube. This part N might be a portion of the breech door B', or it may preferably be a special fitting in the nature of a plug applied detachably to such door. Between this piece N and the aft portion of the torpedo is introduced a slip joint P. This is shown as a telescopic device comprising two members, one slidable within the other, the respective members at their outer ends having ball and socket connections, the one with the connection piece N and the other with a member Q applied to the torpedo. The connection Q is of any suitable socket construction, being preferably carried by the lower vane of the torpedo, and leading from the socket Q is a tube T which enters the torpedo and extends to the opening T' which admits air to the spinning-up turbine R of the gyroscope. The gyroscopic steering gear is of the usual construction, the gyro being enclosed in the usual gyro pot S, and the horizontal steering engine U being mounted on such pot, as shown. The only change in the torpedo itself made by the present invention, is the omission of the usual high pressure air tube for leading high pressure air from the torpedo-starting valve to the admission point T' of the gyroscope-starting turbine; and the substitution of the tube T leading from the socket Q to the same point T'. In all other respects the gyroscope and its supporting means, and the steering engine, are unchanged.

Referring particularly to Fig. 2, the special air tank K is preferably constructed with a charging valve a of any suitable kind, being preferably a duplicate of the charging valve used for charging the air flask of a torpedo. The construction of such charging valves is well understood. A hose or pipe from a compressor or storage tank is connected to the inlet of the charging valve, and the entering air forces itself through this valve into the tank, the valve closing when the charging pressure is relieved. At the bottom of the tank K is provided a blow-off valve b which may be opened by hand to blow out any water which may have accumulated, or to relieve any excess pressure of air. A gauge c is provided, showing the pressure in the tank K. The tank K is provided (preferably on the side opposite the charging valve) with an outlet valve L already referred to, which may be of precisely the same essential construction as the so-called starting valve of a torpedo. Such valve comprises a tappet d carried by a plunger e working in a cylindrical portion f; the tank admission through port g is between the tappet and plunger. The tappet closes against a seat leading to the outlet h which delivers air through tube M to the

connections with the torpedo. The opening of valve L is controlled by a valve j the inlet to which is connected by a tube k with the chamber l above the plunger e. As air is compressed into tank K it leaks past plunger e into chamber l and tube k, its escape being stopped by valve j. On the opening of this valve the compressed air escapes to the atmosphere through outlet m, and this relieves pressure in l and permits the higher pressure in g to lift the plunger and tappet, thus opening the discharge through M to the torpedo. While the valve L is open, air is leaking past plunger e and out through valve j, but this loss is negligible because it occurs only during a fraction of a second while the gyroscope is spinning up. At other times the valves L and j are closed and the air pressure is held.

The valve j may be of any suitable construction of relief valve, preferably closing with the pressure and opened by any suitable means, such as by the provision of an operating lever U which is held out of action by a spring n, and has a rod o entering the casing of valve j to unseat the latter.

The control lever U is preferably so related to the launching control mechanism that it may be utilized both for starting the spinning up of the gyroscope, and for starting the launching of the torpedo. To this end it is best constructed as shown, being pivoted at p on the same pivot pin which carries the unlocking lever H, and having a lug or hook q which takes under the operating arm of this lever, and a stud r which takes over such arm. In the position shown in Fig. 2, the spring n has pressed up the lever U until stopped by contact of its hook u with the under side of lever H, so that spring n coacts with a spring s of lever H to hold the latter in the position for locking the sector G of the lever F. In this position the lug r is lifted above the lever H a sufficient distance so that on pressing down lever U until this lug strikes lever H, the movement is enough to open the valve J and start the spinning of the gyroscope. Ordinarily, at this time the lever H will be locked fast by means of the usual locking pin V or other lock, which prevents accidental operation of lever H, such as might cause a premature launching.

The apparatus may be operated in two ways: (1) With the locking pin V in place, so that lever H is held fast, the pressing down of lever U causes the spinning up of the gyroscope prior to launching and without any possibility of the launching being effected until the operator withdraws the locking pin V, whereupon by a further downward movement of lever U, it carries lever H with it and unlocks sector G, which results in the opening of valve D, thus admitting compressed air from tank C to the

launching tube for expelling the torpedo, thereby accomplishing the launching, and at the same time, through the lever arm F' and rod I, withdrawing the usual lock I' to permit the launching movement of the torpedo. By this means any desired interval of time may intervene between the spinning up and unlocking of the gyroscope, and the actual launching of the torpedo. (2) The pin V may first be withdrawn, whereupon the operator may press down the lever U until it strikes lever H, the effect of which is to start the spinning up, and then by a continued movement of lever U may depress lever H so as to unlock the launching mechanism and accomplish the launching of the torpedo in immediate sequence to the spinning up of the gyroscope. In performing this operation it is only necessary to make sure that the second stage does not occur until a sufficient time has elapsed (usually a fraction of a second or possibly one or two seconds) to insure that the gyroscope shall have been spun up and unlocked before the launching movement of the torpedo begins. This the operator can easily determine by watching the gauge c. Since the gyroscope is spun up by the stored supply of air in tank K, the time required for accomplishing the spinning up and unlocking corresponds to an outflow of air which will cause a certain reduction in pressure, the precise amount of which with any given proportions may be easily ascertained by experiment, so that the operator, having noted such fall of pressure on the gauge, may by a secondary movement of lever U depress lever H when the hand on the gauge has indicated a fall to such pressure. This operation is rendered easy by the fact that spring s is much stiffer than spring n, so that the first movement of the lever U is stopped on meeting lever H, and the operator must then exert greater strength to operate lever H.

It will be understood that the invention is not limited to the use of a special tank such as K for containing a separate charge of compressed air for spinning up the gyroscope; and such spinning may be accomplished by taking air from any suitable source (such, for example, as the tank C), provided only that the flow of the air be under control of a suitable starting valve. The advantage in the use of the special tank K is that the operator may know by the fall of pressure (as stated above) the precise instant at which (as determined by experiment) the gyroscope has been spun up and unlocked. With such special tank the air remaining in the tank after the spinning up and launching of the torpedo is (or may be) permitted to blow out through pipe M into the launching tube, thus avoiding the necessity of providing any more or less complicated means for arresting the flow of air.

The construction of the slip joint or telescopic connection P is practically important. It should be so constructed that when the high pressure of air is admitted, this pressure will have no appreciable effect to force the members of the joint apart, or, in other words, no effect to push the torpedo forward in the launching tube. Its construction must also be such that at almost the beginning of the launching movement of the torpedo the connection may freely slip open or become disconnected, and leave the torpedo free to move out through the launching tube. It should also be of such character that the member of the connection which remains attached to the torpedo shall not interfere with its proper movement or disturb its steering.

These conditions are realized in the construction shown in Figs. 3 and 4. The slip joint P consists of an inner member P' and an outer member P². Preferably it is the inner member which is attached to the torpedo. Each member terminates in a ball t or t', which is received in the appropriate socket, with a suitable allowance for swinging movement to enable the two members to be properly aligned when fitted together. The respective members are formed with bores or ducts for conducting the air through them, comprising a bore u in the member P² branching preferably into two bores u' which terminate as orifices u² opening into the inner chamber or cavity of this member, in which the inner member P' fits. One or other of the members has a band or zone u³ cut away to provide for circulation of air within a certain range of longitudinal movement of the respective members; the inner member P' has lateral orifices u⁴ admitting the air to its longitudinal duct u⁵. The aft end of the member P' is closed at v so that the air cannot escape rearwardly. This has the effect of balancing the pressure in P', since the forward thrust of the compressed air is balanced by its rearward reaction against the closed end v. A good working fit between the telescopic members is all that is required, it being needless to make any special provision against leakage since the period of air supply is so brief; but to avoid any longitudinal thrust due to leakage, the bottom of the chamber w within the outer member is vented to the atmosphere by an orifice w' so that any air leaking into this chamber may escape freely into the launching tube.

The present invention has several important advantages. It enables the course of the torpedo to be determined by the spinning up and unlocking of the gyroscope quite independently of the time or direction of launching, which, especially in a seaway, or when the ship is yawing, enables more accurate firing to be accomplished. It is well under-

stood that the course of the torpedo is determined by the direction in which the gyroscope points at the instant that it is set free by the unlocking movement, and this in ordinary launching is accomplished during the movement of the torpedo through the launching tube; the present invention enables the aiming and spinning up, and unlocking of the gyroscope, to be accomplished at any desired instant, and the launching to follow thereafter in convenient time.

Another advantage is that the effective energy of the torpedo is increased and its range thus extended. The air-spun gyroscope in torpedoes as heretofore constructed, has required approximately six pounds weight of air, and has reduced the air pressure about 50 pounds per square inch. The present invention, by taking air for spinning from outside the torpedo, avoids the loss of this air from the torpedo flask and thereby enables all the stored air to be utilized for propelling the torpedo.

A further advantage is that the torpedo is simplified and loss by leakage is prevented by the removal of a high pressure air pipe from the interior of the torpedo, which pipe heretofore has carried high pressure air from the opening of the starting valve throughout the whole run of the torpedo, so that if any leak occurred there was a material loss of air from the air flask of the torpedo. The pipe T now substituted receives air only temporarily during the brief period of spinning up of the gyroscope, and this comes not from the air flask, but from a source outside the torpedo, and before the launching of the torpedo has been effected the supply of air pressure is cut off therefrom.

An important practical consideration is that these advantages are realized without any material change in the existing torpedo. The gyroscope and its spinning up and unlocking mechanism remain precisely as heretofore, their construction having become standardized. The only change in the torpedo is in the location and source of supply of the pipe which leads compressed air to the spinning-up turbine of the gyroscope.

The present invention is not by any means confined to the precise construction or combinations of parts herein shown and described, it being subject to considerable variation or modification without departing from the essential features which are set forth in the appended claims. For example, the invention is not limited to use with launching tubes which expel the torpedo by compressed air from a flask C, as other means for ejecting the torpedo are known which are equivalent thereto for the purposes of this invention.

I claim as my invention:

1. The combination with a launching tube

and torpedo, the latter having an air-spun gyroscope, of a valve-controlled conduit for conducting compressed air from a source exterior to the torpedo into the torpedo to the means for spinning up its gyroscope, where- 70 by the air for spinning up is taken from a source exterior to the torpedo.

2. The combination with a launching tube and torpedo, the latter having an air-spun gyroscope, of a valve-controlled conduit for 75 conducting compressed air from a source exterior to the torpedo into the torpedo for spinning up its gyroscope, said conduit including a separable connection adapted to open upon the launching movement of the 80 torpedo.

3. The combination of a launching tube, a torpedo having an air-spun gyroscope, a source of compressed air exterior to the torpedo, and controllable means for introducing 85 such compressed air into the torpedo to the means for spinning up the gyroscope.

4. The combination of a launching tube, a torpedo having an air-spun gyroscope, a special compressed air tank, a conduit lead- 90 ing therefrom through the launching tube into the torpedo to the air-inlet of the gyro- scope spinning means, and a manually-con- trolled valve for admitting compressed air through said conduit, whereby the air for 95 spinning up the gyroscope is taken from such special tank instead of from the tor- pedo air flask.

5. The combination of claim 4, the special air tank having charging means and an out- 100 flow valve, and manually-controlled means for operating said valve.

6. The combination of a launching tube, a source of compressed air, a valve for con- 105 trolling admission of such air to the tube, means for releasing said valve to start the launching, a torpedo having an air-spun gyroscope, a conduit for introducing com- pressed air from outside said torpedo to the air-inlet of the gyroscope, spinning means 110 to spin up such gyroscope, and controlling means for admitting compressed air to said conduit.

7. The combination of claim 6, the re- 115 spective controlling means being so related as to insure the admission of compressed air to spin the gyroscope prior to the ad- mission of compressed air to launch the torpedo.

8. The combination of a launching tube, 12 a torpedo having an air-spun gyroscope, a conduit for admitting compressed air from the exterior to the air-inlet of the gyroscope, spinning means to spin up said gyroscope, launching controlling means for said tube, 12 and means for admitting compressed air to said conduit, said respective means con- nected to insure the prior operation of said latter means, whereby the gyroscope is spun up prior to launching.

9. The combination of claim 2, the separable connection comprising telescopic members connected respectively to the torpedo and launching tube and adapted to pull 5 apart during launching.
10. The combination of claim 2, the separable connection comprising telescopic members with air ducts through them connecting laterally through communicating orifices, 10 the inner member being closed at its end to balance the contained pressure and prevent any longitudinal thrust.
11. The combination of claim 2, the separable connection comprising telescopic members with air ducts through them connect- 15
- ing solely laterally through communicating orifices in such manner as to balance the pressure and prevent any longitudinal thrust.
12. The combination of claim 2, the separable connection comprising telescopic members both closed at their ends, the air ducts through them communicating laterally through orifices in the respective members, one member having a circumferential groove 20 maintaining communication between their respective orifices.

In witness whereof, I have hereunto signed my name.

WILLIAM DIETER.
